UNITED STATES PATENT OFFICE.

WILLIAM KLOCKE AND JOHN E. DOBSON, OF NEW YORK, N. Y., ASSIGNEES TO E. W. BLISS COMPANY, OF BROOKLYN, NEW YORK, A CORPORATION OF WEST VIRGINIA.

DRAWING PRESS OR THE LIKE.

1,411,036.

Specification of Letters Patent. Patented Mar. 28, 1922.

Application filed May 17, 1919. Serial No. 297,911.

To all whom it may concern:

Be it known that we, WILLIAM KLOCKE and JOHN E. DOBSON, citizens of the United States of America, residing, respectively, in the borough of Queens and borough of Manhattan, city and State of New York, have invented certain new and useful Improvements in Drawing Presses or the like, of which the following is a specification.

10 This invention relates to improvements in presses, and more particularly to presses of the drawing type, and aims to provide improvements therein.

15 The present invention provides a drawing press in which a reciprocating part (a bed or blank-holder slide) may approach and recede from the extremes of its movement with a gently retarded and accelerated motion, abrupt and sudden applications of force being avoided, and at the same time dwells of relatively considerable duration given to the reciprocating driven part at the extremes of its movement. The invention further provides such a press wherein the 20 dwell at one extreme by the reciprocating driven part may be of greater duration than that at the other end.

25 In fact, the invention provides a press employing toggles and links wherein the positive and negative acceleration of the reciprocating part is relatively uniform at the extremes of the movement of said part, and whereby a dwell of from 120° to 140° of a crank movement may be imparted to said 30 reciprocating part.

35 The invention further provides a press wherein, by a short angular movement of a part connected to a rotative part by a toggle, an angular movement of 180° may be imparted to said rotative part.

40 Other features of the invention will be hereinafter described and embodiments thereof are illustrated in the accompanying drawings and fully described in the following 45 description.

In said drawings,—

46 Figures 1 and 2 illustrate a drawing press embodying the present invention, and employing a reciprocating blank holder slide, 50 Fig. 1 being a view in side elevation, and

Fig. 2 being a front elevation partly in section.

55 Figs. 3, 4 and 5 are views illustrating a drawing press having a stationary blank holder and movable bed, and also embodying the invention, Fig. 3 being a front elevation partly in section, Fig. 4 being a side elevation partly in section, and Fig. 5 being a horizontal sectional view on the line V—V, Fig. 4.

60 Figs. 6, 7, 8 and 9 are explanatory diagrams,

65 Referring to Figs. 1 and 2, numeral 1 designates one of the working parts of the press necessary for drawing, requiring a dwell in its movement, and adapted to carry a tool as for example a blank holder or die, according to the design of the press, 2 a bed, and 3 a punch or plunger working through the blank holder or die-carrying slide. 70

75 The plunger 3 is conveniently given a reciprocating movement by a crank 4 upon a shaft 5, driven from a pulley 6 through a shaft 7, gears 8 and 9, shaft 10, pinion 11 and gear 12.

80 In the operation of a drawing press, it is desirable to have the blank holder press the blank to be drawn, against the bed (or die carried thereby) prior to the punch or plunger striking the blank, and to dwell during the action of the punch upon the blank and until the punch has completed at least a part of its withdrawal from the shaped blank. It is also desirable, especially with large 85 presses where heavy masses are in reciprocating motion, that the reciprocating tool carrying part, as for example, the blank holder or die-carrying slide, be actuated in such a manner as to relatively uniformly accelerate its movement in a positive and negative sense, as it leaves and approaches the extremes of its reciprocation.

90 It is also desirable to produce such a movement of the reciprocating part, as for example, the blank holder slide, by means other than cams, as for example, by toggles. In fact, in drawing presses, the reciprocating blank holders or die-carrying slides (or beds) are now usually actuated by a toggle mechanism, the dwell against the blank being effected by an ar- 100

arrangement of such toggles. By the toggle motion of the present invention, however, there is produced a uniform easing of the reciprocatory motion of the blank holder or die-carrying slide (or bed) at both extremes of its reciprocation, and also a longer and more decided dwell of the reciprocatory blank holder or die-carrying slide (or bed) may be effected in the blank-holding position of said part than with previous toggle drawing presses.

The toggle motion of the present invention comprises a pair of toggles 15 and 16, serially connected, or connected so as to act serially. The leg 17 of the toggle 16 is conveniently directly connected to the reciprocatory part to be actuated, as for example, the blank holder slide, and the other leg 18 of the toggle 16 may be in the form of a crank upon a shaft 19. One leg of the toggle 15 may be in the shape of a crank arm 20, the other leg being a link 21 which is conveniently connected to a guide, as for example, a link 25, pivoted at one side of the press, as indicated at 26.

The actuating force is applied as to act through the series of toggles and is most conveniently applied to the end of the leg 21 of the toggle 15, as indicated at 27. The means for actuating the toggles is preferably a rotary-to-reciprocatory-movement-converting means, and is most conveniently an eccentric pin or crank connected to or upon the same shaft which actuates the punch or plunger, as for example, a crank pin 30 upon the gear 12 upon the crank shaft 5. A connecting-rod or link 31 serves to connect the pin 30 with the leg 21 of the toggle series. By positioning the pin 30 with relation to the crank, the timing and relative movements of the punch or plunger and of the blank holder slide (or bed) may be conveniently and readily effected.

The throw of the crank pin 30, may be equivalent to, or preferably approximates in length, the length of the legs 18, 20 and 21, of the series of toggles, when in extended position. The legs of the toggle at the end of the series at which force is applied are preferably slightly longer than one-half the throw of the crank or equivalent part (in the case where the force is applied at the end 27 of the toggle 16), in order that said toggle at the end of the series at which force is applied will not be completely extended, or closed, when the toggle at the end of the series nearest the reciprocatory part or blank holder is completely extended or completely closed, thereby avoiding the effects of the actuating force being applied in a "dead center" direction.

The arrangement of the toggles is also such that the part applying force to the series, as for example, the link 31, acts in a direction which is substantially circumfer-

ential to the center of the knee of the toggle (15) at that end of the series of toggles at which force is applied, at or near one end of the reciprocatory movement of said force-applying part or means, whereby there is obtained a considerable and decided dwell of the part actuated by the toggle mechanism by reason of the movement of the force-applying part being taken up almost completely by a simple movement of the extreme leg, as for example, the leg 21 around the axis 33 of its knee.

The guide, in the form of a link, as indicated at 25, preferably turns on a long radius, and has a short angular movement as regards the angular movement of the rock shaft 19 to which the toggles are connected.

By referring to Figs. 8 and 9 it will be seen that even more decided effects, as regards the dwell at the end of the reciprocation, may be provided by guiding the end of the leg 21 in an arc described around the axis 33 of its knee, at the end part of the opening movement of the toggle 15 of which said leg 21 is a part. The end of the leg 21 may, during the other part of its movement, be guided in a straight line. The long arc described around the axis on which the guide link 25 turns is really a merger into a single curve of the short curve described by the end of the leg 21 at the final part of its opening movement, and a straight line.

By lengthening the radius of the arc upon which the end of the leg 21 turns at the end part of the opening movement of the toggle 15, the dwell at the corresponding end part of the reciprocatory part actuated by said toggle mechanism may be prolonged, as may be seen from a comparison of Figs. 8 and 9.

Operation: The operation of the toggle movement, and of the drawing press above described employing said movement, will be best comprehended by reference to the diagrams shown in Figs. 6, 7, 8 and 9. Fig. 6 shows the parts at one extreme of the movement of the reciprocatory part 1 (as for example, the blank holder slide), preferably the working position of the reciprocatory part, and Fig. 7 shows the parts in the position which they occupy at the other end of the reciprocatory motion of said reciprocating part. Assuming the actuating force applied to the toggle series to be derived from a crank pin 30 moving around a driven shaft 5, the extent of movement of said crank pin 30, at equal time intervals, will be indicated by the aliquot degree markings at the left-hand side of Fig. 6, and assuming the pin 30 to be revolving in the direction of the arrow, it will act upon the series of toggles through the link 31 to cause said toggles, considered as a whole, to lengthen; the first movement, however, of the toggles being a movement of the leg 21 in an arc or approximately in an arc described around

- the axis 33 of the knee of the toggle 15. The axis 34 of the knee of the toggle 16, and the axis 19 around which said toggles turn, and the reciprocatory part 1 being substantially 5 in line (in which position the part 1 can exert or sustain a maximum force), the movement of the leg 21 around the axis 33, and corresponding to a movement of 60° of said pin 30 (120° movement of the pin 30 10 for two oscillations of the end of the leg 21 from 27° to 27 and back to 27', Fig. 6) will cause no appreciable movement of the points 19, 34 and 1 out of line. The rectilineal 15 advance of the crank pin 30 will accelerate positively to the 180° position, accelerating the movement of the point 27 and the opening of the toggles, but the first part of the movement of the reciprocatory part 1 will be relatively slight as compared with the 20 movement of the point 30 from an angular position of 150° to 180°. During the movement of the point 30 from 150° to 180°, the toggle 15 will be closing and the point 33 will have about the same angular speed as 25 the point 27, (and by flattening the arc of movement of the point 27, the angular travel of the point 33 may be decreased and vice versa). The toggle 16, however, will be just opening, and its point 34 at the knee will 30 travel a maximum angular distance for a given lineal movement of the driven part 1. Therefore, at this part of the movement of the point 30 (i. e. from 150° to 180°) there will be a relatively slow acceleration of the 35 point or part 1. From 180° to about 225° of the point 30, said point 30 will be moving generally in the direction of reciprocation of the point 27, and the points 27 and 33 will still be moving at approximately equal 40 speeds so that the speed of movement is not materially altered by the toggle 15. However, the toggle 16 will be opening with the knee 34 travelling generally in the same direction as the travel of the part 1, and hence 45 the speed of the part 1 will be at its maximum between 150° and 225° of the movement of the point 30. From approximately 225° to 270° there is a negative acceleration 50 of the part of point 1 owing to the point 30 moving generally across the direction of transmission of movement to the point 27, and the knee 34 of the toggle 16 moving generally across the direction of movement of the point or part 1 the speed of the parts 55 30 and 34 being zero at the 270° position. From 270° to 90° the movement of the parts is the inverse of the movement from 90° to 270°.
- From the foregoing it will be perceived 60 that there is obtained at the working end of the reciprocation of the part 1 a practically complete dwell through an angular movement of 120° to 140° of a crank pin revolving uniformly around its axis, and that 65 the reciprocations of the part 1 are initiated
- and terminated at accelerations positive and negative to and from zero motion. There is thereby obtained an easy working of the parts, and an avoidance of sudden or violent change in the movements at the extremes of 70 the reciprocation of the reciprocatory part to be actuated. There is also obtained a pronounced and definite dwell of the reciprocatory part at one end of its reciprocation. Moreover it will be seen that for a relatively small angular movement of the point of application of force to the toggle 15, as the point 27 (see the angle α Figs. 6 and 7) an angular movement of 180° may be imparted to a driven part, as for example, the 80 rock shaft 19.
- In Figs. 3 and 4, numeral 1', designates the reciprocatory part, in this case being the bed of the press, and numeral 2' designates a stationary blank holder. 3 designates 85 the punch or plunger actuated by a crank 4 upon shaft 5, driven as in the embodiment of Figs. 1 and 2. The actuating force may, as in the preceding embodiment, be derived from a crank pin 30 moving the toggle 90 mechanism through a link 31 connected to the end leg 21 of the series of toggles, as indicated at 27'. The bed 1' is actuated the same as the blank holder slide in the embodiment of Figs. 1 and 2, by the serially 95 acting toggles 15 and 16, comprising the legs 17, 18, 20 and 21. Instead of the end of the leg 21 at the end of the series of toggles at which force is applied being guided by a link, the said end of the lever 21 may be 100 guided by a pin and roller 50 travelling in a guide slot 51. This guide slot may conveniently be cut upon an arc similarly to that through which the end of the link 25 moves. Or, this guide slot may be made up 105 of a curved part and a straight, or approximately straight part, as indicated in Figs. 8 and 9.
- The operation of the embodiment shown in Figs. 3, 4 and 5 is the same in principle 110 as explained in regard to the embodiment shown in Figs. 1 and 2. The difference is that the toggle crank 18 is relatively inverted, to give an opposite movement to the part 1'. The invention involves a mechanical movement which may be combined variously with other elements than the parts of a drawing press and said mechanical movement is broadly claimed in our application Serial 115 No. 520,308, filed December 6, 1921.
- It is also obvious that variations may be made in the forms of embodiment specifically illustrated and described without departing from the idea of the invention. 120
- What is claimed is:—
1. A drawing press or the like, comprising a rocking part, a toggle connected thereto, and means for swinging said toggle, comprising a part having a short angular 130

movement, describing an arc generally parallel to the arc described by the swinging end of said toggle connected to said toggle and co-operating to impart a greater angular movement to said rocking part, and a reciprocatory tool carrying part actuated by said rocking-part.

2. A drawing press or the like, comprising a rocking part, a toggle connected thereto, and means for swinging said toggle, comprising a part having a short angular movement, connected to said toggle adapted to impart an angular movement of 180° to said rocking part, and a reciprocatory tool carrying part actuated by said rocking part.

3. A drawing press or the like, comprising a reciprocatory tool carrying part, a rocking part for actuating said part, a toggle connected to said rocking part, and means for swinging said toggle, comprising a part having a short angular movement, describing an arc generally parallel to the arc described by the swinging end of said toggle, connected to said toggle and co-operating to impart a greater angular movement to said rock-shaft.

4. A drawing press or the like, comprising a reciprocatory tool carrying part, a pair of toggles, one of which is a swinging toggle, serially connected for actuating said reciprocatory part, and means applying force to said swinging toggle, said toggles being so arranged that the pivots of each of said pairs of toggles approximate alinement during the time said reciprocatory part is at one extreme of its movement.

5. A drawing press or the like, comprising a reciprocatory tool carrying part, a pair of toggles, one of which is a swinging toggle, serially connected for actuating said reciprocatory part, and means applying force to said swinging toggle, said toggles being so arranged that the pivots of each of said pairs of toggles respectively approximate alinement during the time said reciprocatory part is at the extremes of its movements, one of said toggles being longer than the other.

6. A drawing press or the like, comprising a reciprocatory tool carrying part, a pair of toggles, one of which is a swinging toggle, serially connected for actuating said reciprocatory part, and means applying force to said swinging toggle, said toggles being so arranged that the pivots of each of said pairs of toggles approximate alinement during the time said reciprocatory part is at the extremes of its movements, one of said toggles having an opening movement while the other remains with its axes substantially in line.

7. A drawing press or the like, comprising a reciprocatory tool carrying part, a pair of toggles serially connected for actuating said reciprocatory part, and means ap-

plying force to said reciprocatory part through said toggles, said toggles being connected on a fixed axis, and the knees of said toggles being movable approximately 180° around said fixed axis.

8. A drawing press or the like, comprising a reciprocatory tool carrying part, a pair of toggles serially connected for actuating said reciprocatory part, and means applying force to said reciprocatory part through said toggles, said toggles being connected on a fixed axis, and the knees of said toggles being movable approximately 180° around said fixed axis, the angular movement around the fixed axis by one knee 80 partially overlapping the arc included in the angular movement of the other knee.

9. A drawing press or the like, comprising a reciprocatory tool carrying part, a pair of toggles serially connected for actuating said reciprocatory part, and means applying force to said reciprocatory part through said toggles, said toggles being connected on a fixed axis and the knees of said toggles being movable approximately 180° 90 around said fixed axis, and means guiding the extreme leg of the series.

10. A drawing press or the like, comprising a reciprocatory tool carrying part, a pair of toggles serially connected for actuating said reciprocatory part, and means applying force to said reciprocatory part through said toggles, said toggles being connected on a fixed axis and the knees of said toggles being movable approximately 180° 100 around said fixed axis, and means guiding the extreme leg of the series in a flat arc.

11. A drawing press or the like, comprising a reciprocatory tool carrying part, a pair of toggles serially connected for actuating said reciprocatory part, and means applying force to said reciprocatory part through said toggles, said toggles being connected on a fixed axis and the knees of said toggles being movable approximately 180° around said fixed axis, and means guiding the extreme leg of the series in a flat arc having its center substantially in a straight line drawn perpendicular to the direction of reciprocation at the fixed axis of said toggles.

12. A movement for drawing presses or the like, comprising a reciprocatory tool carrying part, a pair of toggles serially connected for actuating said reciprocatory part, and means applying force to said reciprocatory part through said toggles, said toggles being connected on a fixed axis and the knees of said toggles being movable approximately 180° around said fixed axis, and means guiding the extreme leg of the series, said guide having a curvature at one part which substantially coincides with an arc drawn around the axis of a knee on one of said toggles at approximately an extreme of its movement.

13. A movement for drawing presses or the like, comprising a reciprocatory tool carrying part, a pair of toggles serially connected for actuating said reciprocatory part, and means applying force to said reciprocatory part through said toggles, said toggles being connected on a fixed axis, and the knees of said toggles being movable approximately 180° around said fixed axis, and means for causing the end of the extreme leg of the toggle at the force-receiving end of the series to move in an arc substantially parallel to its other leg at an extreme of the movement of said series of toggles.
14. A drawing press, or the like, comprising a rocking part, a toggle connected thereto, a part having a short angular movement, connected to said toggle, adapted to impart a greater angular movement to said rocking part, and a reciprocatory tool carrying part actuated by said rocking-part, said rocking part and the part having the short angular movement being so arranged that the angular movements thereof are substantially symmetrical with relation to two planes passing through the axis of said rocking part.
15. A drawing press, or the like, comprising a rocking part, a toggle connected thereto, a part having a short angular movement, connected to said toggle, adapted to impart a greater angular movement to said rocking part, and a reciprocatory tool carrying part actuated by said rocking part, said rocking part and the part having the short angular movement being so arranged that the angular movements thereof are substantially symmetrical with relation to a plane passing through the axis of said rocking part.
16. A drawing press or the like, comprising a rocking-part, a toggle connected thereto, and means for swinging said toggle connected to said toggle, the joint between said toggle and swinging means having a line of movement substantially parallel to the arc of movement of said joint around the knee of said toggle at one extreme of movement, and a reciprocatory tool carrying part actuated by said rocking-part.
17. A drawing press or the like, comprising a rocking part, a toggle connected thereto, means for swinging said toggle, comprising a connection between said toggle and swinging means, said connection having a short angular movement, and said means acting to impart a greater angular movement to said rocking part, and a reciprocatory tool carrying driven part actuated by said rocking part.
18. A drawing press or the like comprising a punch driving shaft, a reciprocatory tool carrying slide, and means for reciprocating the same, said means comprising a rocking part, a toggle connected thereto, means for swinging said toggle, comprising a part having a short angular movement describing an arc generally parallel to the arc described by the swinging end of said toggle, connected to said toggle and cooperating to impart a greater angular movement to said rocking part, and a link connecting said punch driving shaft and said part having the short angular movement.
19. A drawing press or the like comprising a side frame, a punch driving shaft extending through said side frame to the other side thereof, a wheel on said shaft on the outer side of said frame, a reciprocatory tool carrying slide and means for reciprocating the same, said means comprising a rocking part, a toggle connected thereto, means for swinging said toggle, comprising a part having a short angular movement describing an arc generally parallel to the arc described by the swinging end of said toggle, connected to said toggle and cooperating to impart a greater angular movement to said rocking part, and a link having a driving connection with said shaft at the outer side of said wheel and to said part having the short angular movement.
20. A drawing press or the like comprising a punch driving shaft, a reciprocatory tool carrying slide, a pair of toggles, one of which is a swinging toggle, serially connected for actuating said reciprocatory slide, said toggle being connected on a fixed axis and being so arranged that the pivots of each of said pairs of toggles approximate alignment during the time said reciprocatory slide is at an extreme of its movement, one of said toggles having an opening movement while the other remains with its axes substantially in line, a part having a short angular movement guiding the swinging end of said swinging toggle, and a driving connection between said punch driving shaft and part with the short angular movement.

In witness whereof, we have hereunto signed our names.

WILLIAM KLOCKE.
JOHN E. DOBSON.
